UNITED STATES PATENT OFFICE.

HUBERT M. GREIST, OF NEW HAVEN, CONNECTICUT.

LAMP FIXTURE.

Application filed January 15, 1923. Serial No. 612,638.

To all whom it may concern:

Be it known that I, HUBERT M. GREIST, a citizen of the United States, residing at New Haven, in the county of New Haven and State of Connecticut, have invented a new and useful Improvement in Lamp Fixtures; and I do hereby declare the following, when taken in connection with the accompanying drawings and the characters of reference marked thereon, to be a full, clear, and exact description of the same, and which said drawings constitute part of this application, and represent, in—

Fig. 1 a plan view of a lamp fixture constructed in accordance with my invention.

Fig. 2 a sectional view on the line 2—2 of Fig. 1.

Fig. 3 a broken sectional view, illustrating one means of connecting the ends together.

Fig. 4 a plan view of one member of the fixture detached, and shown as it is cut from sheet-metal.

Fig. 5 a broken sectional view, illustrating a modified form of connecting the edges.

Fig. 6 a broken sectional view, showing the edges overlapping.

This invention relates to an improvement in lamp fixtures, and particularly to bases and shades for lamp fixtures. The object of the invention is to produce the devices from sheet-metal, so that they may be readily stamped up, and of such a character that they will be sufficiently rigid for the purpose desired, and the invention consists in the construction as hereinafter described and particularly recited in the claims.

The base or shade is formed in two parts, struck up from sheet-metal, each in the form of an X, so that the parts may be cut from a comparatively narrow strip of metal. The ends 10 flare outward and have inwardly-curved edges 11, each end resembling the petal of a flower. Two members are arranged at right angles to each other, so as to form a circle, and are united at their centers, which may be offset, so as to produce a smooth surface. The arms are then curved downward, which brings the edges of the arms close together, the curved edges 11 forming a series of openings around the

shade or base. To give the device additional strength, the ends may be formed with inwardly-turned ears 12, through which a wire ring 13 may be passed, the ends of which will be connected together, so as to hold the arms against spreading, or, instead of forming the ears 12 and using the ring 13, the members may be formed—one with an inwardly-extending, slotted lug 14 and the other with an inwardly-extending offset-finger 15, which may be passed through the slot in the lug 14, so as to interlock the edges. It is also evident that the outer ends of the arms may be made wider, or the ends brought together, so as to overlap, as shown in Fig. 6 of the drawings. This overlapping will tend to strengthen the device, as one member will reinforce the next adjacent member against inward or outward thrusts.

The device, to be used as a shade, may be lined with any suitable material, which will be exposed through the openings between the edges of the members, thus giving a very pleasing effect, and adding to the simulation of a flower.

The fixture elements, thus formed, have the advantage of lightness, as they are struck from comparatively thin sheet-metal; can be produced at a very low cost, and provide a lamp-base or lamp-shade of a very ornamental character.

I claim:

1. A lamp fixture comprising two X-shaped members arranged at right angles to each other, and connected together, the ends of the members being longitudinally-bowed.

2. A lamp fixture comprising two X-shaped members arranged at right angles to each other, and connected together, the ends of the members being longitudinally-bowed, and the ends of the arms connected together.

3. A lamp fixture comprising two X-shaped members arranged at right angles to each other, the ends of the members expanded and their adjacent edges inwardly-curved, and the said members longitudinally-bowed, whereby the edges of the ends are brought together.

4. A lamp fixture comprising two X-

shaped members arranged at right angles to each other, the ends of the members expanded and their adjacent edges inwardly-curved, the said members longitudinally-bowed, whereby the edges of the ends are brought together, and means for connecting the said edges.

In testimony whereof I have signed this specification in the presence of two subscribing witnesses.

HUBERT M. GREIST.

Witnesses:

FREDERIC C. EARLE,
MALCOLM P. NICHOLS.
